UNITED STATES PATENT OFFICE.

EVERETT E. PARKER, OF CHICAGO, ILLINOIS, ASSIGNOR, BY MESNE ASSIGNMENTS, TO
METROPOLITAN TRUST COMPANY, TRUSTEE, OF NEW YORK, N. Y., A CORPORATION
OF NEW YORK.

PRESSING MACHINE.

Application filed September 11, 1916. Serial No. 119,489.

To all whom it may concern:

Be it known that I, EVERETT E. PARKER, citizen of the United States, residing at Chicago, in the county of Cook and State of Illinois, have invented certain new and useful Improvements in Pressing Machines, of which the following is a specification.

This invention relates to pressing machines and more particularly to machines for pressing garments, although capable of use for pressing fabrics of any kind.

The object of the invention is to provide an improved machine which withdraws the steam, moisture and water of condensation from the garment and from the fabric pads of the pressing members and thereby reduces the tendency of the pads to retain moisture, which more quickly dries the garment and prevents puckering of the seams, as would be the case if the moisture were allowed to evaporate slowly; which accelerates the pressing operation and enables the garment to be safely put on and worn immediately after pressing; and which also prevents escape of steam and vapor into the room. A further object of the invention is to provide a machine of this kind in which the application of suction or vacuum for withdrawing the steam and moisture is automatically controlled and requires no special attention or operation by the operator, but is caused or controlled by the normal operation of the machine itself so that said suction is effective at the proper and no other times.

Further objects of the invention are in part obvious and in part will appear more in detail hereinafter.

In the drawings, which represent one embodiment of the invention, Fig. 1 is a side elevation showing the head elevated. Fig. 2 is a front elevation, partly in section, showing the head depressed. Fig. 3 is a plan view of the upper portion of the machine; Fig. 4 is a detail sectional view of the head on the line 4—4, Fig. 3; Fig. 5 is a detail section on the line 5—5, Fig. 1; and Fig. 6 is a detail sectional view, on a larger scale, of the steaming valve, and Fig. 7 is a side elevation, showing a modification.

The machine shown in the drawings comprises a suitable frame 1 near the front of which is located a column 2 supporting the lower pressing member or buck 3 and which

is of common form, being provided with a hollow heating chamber 4 connected to a suitable source of steam supply, such as the pipe 4^a. The upper wall 5 of the heating chamber separates it from a steaming chamber 6 having a perforated upper plate 7 on which is laid the padding 8. Steam may be admitted to said chamber 6 and discharged through the perforated plate 7 and distributed over and across the garment lying on the padding by opening a valve 9 controlling one or more ports in the wall 10 between said chambers, said valve being operated by a rod 11 connected to a foot treadle 12 and being normally held to its seat by a spring 13.

At the back of the frame is a column 14 forming a support for the lever 15, one arm of which carries the upper pressing member or head 16 balanced by a weight 17 on the other arm. The head may be advanced or depressed into pressing relation with the buck by any suitable operating mechanism, the drawings showing for this purpose two toggle links 18 connected by a link 19 to a lever 20 pivoted in the frame and connected by a link 21 to the foot treadle 22. The head is normally held elevated by the usual tension spring or springs 23.

The head is of substantially the same form as the buck, being provided with a heating chamber 24 communicating with a suitable source of steam supply such as the inlet and outlet pipes 25, 26 which are provided with swivel joints 27 on the axis of turning movement of the lever 15. The bottom wall 28 of the heating chamber is also the upper wall of a separate suction chamber 29 having a bottom perforated plate 30 to which the padding 31 is applied. This chamber 29 communicates with a pipe 32 which may be connected by branches to both ends of said chamber but is shown as passing through the center of the back wall of the chamber and directly through the heating chamber 24. Said pipe leads to swivel joints 33 and thence through a valve 34 to a suitable source of vacuum or suction, such as the fan or blower 35. When the valve is opened suction is effective in the chamber 29 and draws into said chamber and out to the exhaust any steam or vapor between the head and buck or any moisture or vapor in or on the garment or the pads of the press-

ing members. Said valve is preferably opened only when the steam supply is on or moisture is present. It may be operated by hand, if desired, but preferably is controlled or operated automatically so that the suction is made effective whenever steam is supplied to the garment, thereby doing away with the necessity of the operator manipulating a separate device for producing the suction effect. Said valve may be controlled or operated by either the steam supply controlling devices or by the mechanism for operating the movable press head. It is shown as provided with a valve rod 36 connected by a clevis 37 to an arm 38 on one end of a shaft 39 whose opposite end has an arm 40 with a toe 41 lying beneath the foot treadle 22. A tension spring 42 normally holds the valve closed.

20 In the upper position of the treadle 22 it is above the toe 41 and during the early downward movement of the treadle to bring the head down to the garment on the buck said treadle has no effect upon the vacuum valve. During the final motion of the treadle, however, it engages the toe 41 and turns shaft 39, thereby opening the vacuum valve. Any steam which may be supplied to the garment or any moisture on the garment or padding is quickly withdrawn by the suction pump, thereby keeping the pads dry and drying the garment quickly before it puckers at the seams and with the best pressing results. The garment may be safely put on and worn immediately after pressing. Moreover the steam and moisture do not escape to the atmosphere and will not affect the health of the operator or injure the walls or furniture in the room.

40 When the head operating lever is released and moves upwardly the vacuum valve closes and cuts off the suction without requiring any attention by the operator. The vacuum is therefore effective for short intervals when the flashes of steam are turned upon the garment and does not affect the heating of the pressing head by the steam supply to its heating chamber as will be readily understood.

50 Fig. 7 shows a modified form of the invention in which the vacuum valve is operated by one of the toggle links instead of by the pressure treadle. The pipe 43 communicates through the edge of the head with the vacuum chamber therein. Said pipe may be a flexible metallic hose leading directly to the vacuum valve but is shown as passing to a swivel joint 44 on the axis of swinging movement of the head carrying lever, thence to the vacuum valve 45 and thence to the pump or fan 35. The valve has an operating handle 46 normally moved to the position shown in dotted lines by a spring 47. When the press is opened one of the toggle links connected

to the pivot 48 engages a toe 49 on the valve handle and turns it to the position shown in full lines, thereby closing the valve 45, whereby the suction becomes ineffective. When the press is closed the handle 46 is released and spring 47 opens the valve.

What I claim is:

1. A pressing machine, comprising relatively movable pressing members, each provided with a foraminous pressing wall and an inner chamber communicating with the atmosphere through the openings in said wall, means for supplying steam to the chamber in one of said members, means for producing suction in the chamber in the other member, means for producing relative pressing movement between said members, and means actuated by said member-moving means for rendering said suction effective when said members are in pressing relation with each other. 75

2. In a pressing machine, a buck having a steam heated chamber and a steam distributing chamber, the latter chamber having an outlet for applying steam to a garment on the buck, means for controlling the entrance of steam to the distributing chamber, and means movable about an axis at the rear of the buck and to and from the surface thereof whereby air may be caused to flow over said surface and a garment thereon. 90

3. A pressing machine, comprising relatively movable pressing members, each provided with a foraminous pressing wall and an inner chamber communicating with the atmosphere through the openings in said wall, means for supplying steam to the chamber in one of said members, means for producing suction in the chamber in the other member, means for producing relative pressing movement between said members, and means actuated by said member-moving means for rendering said suction effective only when said members are in pressing relation with each other. 100

4. In a pressing machine, a buck having a steam heated chamber and a steam distributing chamber, the latter chamber having an outlet for applying steam to a garment on the buck, means for controlling the entrance of steam to the distributing chamber, and a hollow member movable about an axis at the rear of the buck to and from the surface thereof and through which air may be caused to flow over said surface and a garment thereon. 115

In testimony whereof I affix my signature.

EVERETT E. PARKER.
